G. E. HULSE.
SAFETY VENT FOR EXPANSION DRUMS.
APPLICATION FILED JUNE 24, 1907.

Patented July 5, 1910.

UNITED STATES PATENT OFFICE.

GEORGE E. HULSE, OF NEWARK, NEW JERSEY, ASSIGNOR TO SAFETY CAR HEATING & LIGHTING COMPANY, A CORPORATION OF NEW JERSEY

SAFETY-VENT FOR EXPANSION-DRUMS.

962,045.

Specification of Letters Patent.

Patented July 5, 1910.

Application filed June 24, 1907. Serial No. 380,597.

To all whom it may concern:

Be it known that I, GEORGE E. HULSE, residing at Newark, in the county of Essex and State of New Jersey, have invented 5 certain new and useful Improvements in Safety-Vents for Expansion-Drums, of which the following is full, clear, and exact description, such as will enable others skilled in the art to which it appertains to 10 make and use the same.

This invention relates broadly to safety valves but more especially to a valve adapted automatically to relieve abnormal pressures occurring in the expansion tanks of 15 water circulating systems.

One of the objects of my invention is to provide a device of the above character, such that while the same is entirely sure and reliable in its operation, it will automatically re-set itself after the abnormal pressure in the system has been relieved. 20

Another object is to provide a safety vent particularly adapted for use with water circulating systems employed in railway cars 25 or like structures in which the cost of maintenance is reduced to a minimum and which may be set to vent at any desired pressure.

Other objects will be in part obvious and 30 in part pointed out hereinafter.

The invention accordingly consists in the features of construction, combinations of elements and arrangements of parts which will be exemplified in the construction hereinafter set forth, and the scope of the application of which will be indicated in the following claims.

In the accompanying drawings wherein is 40 illustrated one of the various possible embodiments of my invention: Figure 1 is a vertical sectional view of the same, Fig. 2 is a top plan view of the lower portion of the casing thereof. Fig. 3 is a view of the same in side elevation.

Similar reference characters refer to similar parts throughout the several views of the drawing.

Referring now to the drawing wherein I have shown a safety vent for water circulating systems, particularly adapted for employment with heating systems of the so-called Baker type 1 indicates a casing the lower portion of which is externally threaded as at 2 and adapted to be threaded into 50 the expansion tank of the heating system.

An inlet passage-way 3 leads upwardly through this casing into a chamber 4 formed by the inner walls of the casing and a flexible diaphragm 5 stretched across the upper portion thereof and resting at its outer 60 edges upon an internal shoulder 6 of the casing. The diaphragm is held in position by means of a cap piece 7 which rests thereon above shoulder 6, said cap piece being firmly clamped in position by means of a 65 shouldered ring 8, a shoulder 10 of which engages an opposed shoulder 11 of the cap piece, said ring having a threaded engagement with the upper portion of the casing exteriorly thereof.

Leading from the central portion of chamber 4 is an outlet passage-way 12 which discharges into the atmosphere. The inner terminal of passage-way 12 is raised as shown at 13 and formed into a tapered valve seat 75 upon which the central portion of the flexible diaphragm is adapted to rest, said portion constituting a valve to close said passage-way. The diaphragm is held in engagement with its seat by means of a block 80 14 the lower portion of which is shaped to conform to the shape of the valve seat, said block having a shoulder 15 against which a coil spring 16 seats, the opposite end of said spring seating against a similar 85 block 17, which in turn engages the lower end of an adjusting screw 18 threaded on the upper portion of cap piece 7. A lock nut is threaded upon adjusting screw 18 and takes against the upper surface of cap piece 90 7. The upper portion of adjusting screw 18 is squared or otherwise shaped to accommodate a wrench or other turning implement and a protecting cap piece 19 covers the upper end of the adjusting screw and 95 has threaded engagement exteriorly of cap piece 7.

The operation of this embodiment of my invention which should to a large extent be obvious from above description is substantially as follows. It is to be understood, of course, that the diaphragm is normally held in the position shown by means of the coil spring and that the adjusting screw 18 may be set to hold the diaphragm in such 105 position with any desired degree of pressure so that the same will be raised to vent at a pre-determined pressure within the expansion tank. Upon the occurrence of such abnormal pressure within the expansion tank 110

the internal pressure within chamber 4 will operate to lift the diaphragm which in turn will lift block 14 against the tension of its spring whereby the compressed fluid 5 will be allowed to vent through discharge passage-way 12 to the atmosphere.

It will accordingly be seen that I have provided a construction well adapted to attain among others the above mentioned objects and ends of my invention in an exceedingly simple and efficient manner.

Owing to the fact that the internal pressure within the chamber of the casing acts upon a large portion of the diaphragm exterior to the portion thereof which rests against the valve seat, same will be gradually raised from its seat thereby removing any liability of the same to become fast thereon. The flexible diaphragm moreover acts in the nature of a packing between the spring pressed block and the valve seat, insuring a tight closing for the vent. While I have shown my improved vent in the above relation, it is obvious that the same may be employed to great advantage in other analogous relations although it is particularly adapted for use in the relation shown.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

Having described my invention, what I claim as new and desire to secure by Letters Patent is:—

1. In a safety vent for water circulating

systems, in combination, a casing adapted to be connected with the expansion tank of a water circulating system, a chamber provided within said casing, one wall of which is constituted by a flexible diaphragm, a passage-way leading from the expansion tank to said chamber, a passage-way leading from said chamber to the atmosphere, said latter passage-way having a tapered valve seat formed upon its inner terminal, a portion of said diaphragm resting upon said valve seat, a block shaped to conform with said valve seat located upon the opposite side of said diaphragm and adapted to hold the same in contact with said seat, a coil spring engaging said block, and means for adjusting the tension of said spring.

2. In a vent for water circulating systems, in combination, a casing adapted to be connected with the expansion tank thereof, having a chamber in communication with the expansion tank by means of a passage-way leading through said casing, said casing also having a passage-way leading from said chamber to the atmosphere, a partially tapered valve seat provided upon the inner terminal of the latter passage-way, a flexible diaphragm stretched across said chamber and forming a wall thereof, the central portion of said diaphragm resting upon said valve seat and constituting a valve therefor, resilient means for pressing said diaphragm against said seat, comprising a pair of opposed blocks one of said blocks being shaped to conform with said valve seat, a coil spring interposed between said blocks, a set screw engaging said blocks, said set screw being adapted to be operated to adjust the tension of said spring, and a cap covering said set screw.

In testimony whereof I affix my signature, in the presence of two witnesses.

GEORGE E. HULSE.
